UNITED STATES PATENT OFFICE.

WOLCOTT A. HULL AND ARTHUR G. BOYER, OF NEW YORK, N. Y.; SAID
BOYER ASSIGNOR TO SAID HULL.

PRESS FOR SHAPING PLASTIC MATERIAL.

SPECIFICATION forming part of Letters Patent No. 447,187, dated February 24, 1891.

Application filed February 6, 1890. Renewed January 22, 1891. Serial No. 378,626. (No model.)

To all whom it may concern:

Be it known that we, WOLCOTT A. HULL and ARTHUR G. BOYER, both of New York, in the county and State of New York, have invented a certain new and useful Improvement in Presses for Shaping or Forming Plastic Material, of which the following is a specification.

This improvement relates to presses designed for shaping or forming plastic material, such as yeast-cakes.

We will describe a press embodying our improvement, and then point out the novel features in claims.

In the accompanying drawings, Figure 1 is a front elevation of a press embodying our improvement. Fig. 2 is a sectional elevation taken in the plane parallel with that of Fig. 1 and showing the parts of the press in the starting position, or, in other words, in that position which they occupy during the feeding or supplying of material. Fig. 3 is a view similar to Fig. 2, showing the parts in the positions which they assume after occupying the positions represented in Fig. 2. Fig. 4 is a view similar to Figs. 2 and 3, showing the parts in the positions which they occupy at the completion of the pressing operation. Figs. 2, 3, and 4 are somewhat peculiar views, in that the upper and lower portions are represented as they would appear in a front view, and the intermediate portion is represented in vertical section. Fig. 5 is a plan of a portion of a movable plate comprised in the press. Fig. 6 is a vertical section taken at the plane of the line *v v*, Fig. 5. Fig. 7 is a horizontal section taken at the plane of the dotted line *w w*, Fig. 6. Fig. 8 is a vertical section of a portion of a fixed mold-plate, a portion of the movable plate before mentioned, and two end sections or plungers operating with said plates, these end sections or plungers being represented as having portions of their length removed, so as to economize space in the drawing, and thereby enable them to be represented on a large scale. Fig. 9 is a top view of one of the end sections or plungers. Fig. 10 is a central vertical section of an end section or plunger of modified construction. Fig. 11 is a top view of the end section or plunger illustrated in Fig. 10. Fig.

12 is a view similar to Figs. 2, 3, and 4, but it illustrates a different construction. Fig. 13 is a vertical section, on an enlarged scale, of a portion of one of the elements of the machine represented in Fig. 12. Fig. 14 is a top view of one section of the part represented in Fig. 13.

Similar letters of reference designate corresponding parts in all the figures.

Referring first to Figs. 1 to 9, inclusive, A designates what we term the "movable plate" of the press. B designates the fixed mold-plate, and C' C² designate end sections or plungers. The movable plate and fixed plate each has a number of cavities, and the end sections or plungers correspond in number and position with these cavities. Material to be pressed is introduced into the movable plate. At the starting of the press the lower end sections or plungers extend within the cavities of the movable plate, closing the lower ends thereof. Material to be pressed is introduced into the movable plate above the lower end sections or plungers. The lower end sections or plungers and the movable plate together rise, and by this motion some of the material will be forced into the cavities of the fixed plate. The remainder of the material will be forced into the fixed plate by the subsequent rising of the lower end sections or plungers through the movable plate, and after all the material has been forced into the fixed plate it will be compressed therein by the two series of end sections or plungers and so molded.

Having given this general description, which we believe will facilitate an understanding of the press, we will proceed to give a more detailed description of the same.

The fixed mold-plate B may advantageously be of rectangular form and supported by upright posts D. There will preferably be four of these posts, and the corners of the fixed mold-plate will be provided with lugs made hollow to fit the posts. The plate can then be secured in a fixed position upon the posts by means of set-screws b, fitting tapped holes in the lugs of the plates and impinging against the posts. Obviously by loosening the set-screws provision will be afforded for adjusting the plate vertically upon the posts to a

new position, and the tightening of the set-screws again will effect the retention of the plate in the new position.

In the present instance the press is constructed with a special view of pressing yeast-cakes, and so the cavities of the fixed plate are made elliptical, as indicated in Fig. 7.

The movable plate A has cavities similar to those of the fixed plate B, these cavities being represented by Fig. 7 and corresponding in position to the position of the cavities in the fixed plate. The upper surface of this plate is divided off into rectangular spaces, which are separated by very narrow edges 15 a' . (See particularly Figs. 5 and 6.) These rectangular spaces communicate with the cavities and are contracted downwardly to the contour of the cavities, so that they form flaring mouths of rectangular form for the 20 cavities. As shown, these flaring mouths are made in a section, which is separate from the main portion of the plate; but this is a non-essential feature, and, indeed, the flaring mouths may be entirely dispensed with in 25 the treatment of some materials.

The movable plate A is supported by a number of springs E, here shown as surrounding bolts or rods F, that extend upwardly and are supported by a movable part of an engine R', 30 here represented as made in the form of a hydraulic ram. As here shown, the bolts or rods F extend upwardly from a gas-chamber G², that is carried by the movable part of the engine, and they enter a base-flange a , with 35 which the movable part A is provided. The springs E surround these bolts or rods between the top of the gas-chamber G² and the flange a of the movable plate. Nuts applied to the upper ends of the bolts or rods may be 40 adjusted to vary the range of movement of the movable plate. The particular manner in which the springs E are arranged to support the movable plate A is not material, so long as these springs are intermediate of the 45 movable plate and a movable part of the engine.

H designates a receiver for material to be pressed. It is made in the form of a frame, which conforms in shape to the extremity of 50 the movable plate and fits snugly around the same. This frame is supported by springs, so that it may yield automatically. In the present instance it is supported by springs I, which surround rods or bolts J, that extend 55 from the base-flange a of the movable plate A upward through a flange h , with which the receiver H is at its base provided. Nuts applied to the upper end of these rods or bolts may be adjusted to alter the range of movement of the receiver. When the machine is 60 ready to start, as represented in Fig. 2, this receiver H is forced upwardly by the springs I and extends above the movable plate. It is then in position to receive the material which 65 is to be pressed. The material introduced into the receptacle H will descend into the cavities of the movable plate.

While the part a may be a mere base-flange, as heretofore explained, yet it may be constructed independently of the receptacle 70 proper and merely as a yielding support to the same. In the latter case the receptacle could be removed without removing the flange or support a .

The movable part r' of the engine R' has 75 attached to it a plate or platform r^3 , which, as here shown, is provided at the corners with hollow lugs that fit in the posts D. This platform r is moved vertically by the engine and is guided in its travel by the posts. The gas-chamber G² is mounted upon this platform r^3 , and of course carried thereby. At the top 80 of the press is another engine R², supported on a platform P. This engine may advantageously be an air-engine. It has a piston-rod r^4 , which is connected with a plate or platform r^4 , that is fitted to slide vertically upon the posts D. The gas-chamber D' is secured 85 to the plate r^4 .

The engine R² is provided with a rotary 90 valve, which has a stem r^5 , that protrudes through the case. A volute spring r^6 is attached to this stem and also to the platform P. The stem has attached to it a wheel r^7 . A cord r^8 is attached to this wheel r^7 , wound 95 around the same, passed thence around a guide-pulley r^9 , thence around a guide-pulley r^{10} , and at the extremity is fastened to the platform r^3 , that is operated by the engine R'. The cord is connected to the platform r^3 by having attached to its end a bolt that extends through 100 a plate which is secured to the platform r^3 , a nut being applied to the bolt beneath said plate, so as to adjustably connect the bolt with the said platform. 105

It is obvious that during the descent of the platform r^3 the cord r^8 will move the valve of the engine R² in one direction, and that as the platform r^3 moves upwardly the spring r^6 will operate the valve in the reverse direction. The valve may at any time be moved by hand in the direction in which it is moved by the descent of the platform r^3 if the cord is suitably pulled. Any other suitable means for automatically moving the valve of the engine may be used. 115

The two series of end mold-sections or plungers C' C² are attached, respectively, to the gas-chambers G' G² and move therewith. Gas is supplied to the gas-chambers by pipes 120 g' g^2 , which are connected by flexible pipes g with a source of supply. The gas used may be air under pressure and may come from the same source of supply as that by which the engine R² is operated when the latter is of 125 such character as to be operated by air or other gas. The supply of gas to the chamber G' is controlled by a valve g^3 , fitted to the pipe g' , and having a protruding stem, which, on the downward movement of the gas-chamber G' 130 to a certain point, will contact with a fixed stop g^4 , and thereby be pressed inward so as to admit gas. On the reverse movement of the gas-chamber G' the valve will close auto-

matically. The stop g^4 is here shown as provided with a collar that fits around one of the posts D and is retained in position thereon by means of a set-screw. When so made and combined with a post D, it is of course adjustable. This is advantageous, because it affords the machine a capacity of adjustment. The manner in which the valve will contact with the stop may be readily understood by reference to Figs. 1 and 2, and the effect upon the valve of an upward movement of the gas-chamber G' may be seen in Figs. 3 and 4.

The supply of gas to the chamber G² is controlled by a valve g^5 , fitted to the pipe g^2 . This valve is opened automatically by means of a stop g^6 , attached to the flange a of the movable plate A. This stop is carried upward by the upward movement of the movable plate; but upon this upward movement of said plate being arrested becomes a fixture, and in the second upward movement of the valve with the gas-chamber G² the stem of the valve contacts with the stop and results in the opening of the valve. The valve is closed by a spring, aided by the pressure of the gas itself. The opening of the valve is illustrated in Fig. 4. In the other figures it is closed.

The stop g^6 consists of a rod bent outwardly from the flange a of the movable plate and turned downwardly at the outer extremity. The outer extremity is screw-threaded and a ball-shaped nut is fitted thereto. This nut may be adjustable to vary the time of the opening of the valve. A similar nut may advantageously be used as a part of the stop g^4 .

The end sections C' C² are substantially similar in construction. Each one of these end sections or plungers consists of a body portion c and a shank portion c'. In Figs. 1, 2, 3, 4, and 5 the body portion is shown as made quite long and the shank portion comparatively short. The body portion may be made short and the shank portion long, as represented in Figs. 8 and 10. Preferably the body portion will be made independently and attached by means of screw-threads or otherwise to the shank portion, as in this way provision will be afforded for pressing articles of different shapes without introducing complete end sections or plungers into the press.

The operative extremities of the end sections or plungers represented in the drawings are constructed of such shape as to form the ends of an ellipsoidal article, and therefore have cup-shaped cavities c², which are elliptical at the extremities. From the cup-shaped cavity of each end section or plunger an opening or passage c³ extends to the extremity of the shank. At the junction of the passage c³ with the cavity c² a valve V' is arranged. The stem v of this valve extends through the passage c³, and at the outer extremity beyond the shank portion of the end section has fitted to it a valve V². This valve V² may be made in the form of a disk, secured by a screw-thread within itself or by

screw-threads formed upon nuts applied on each side of it to the stem. It may even be slipped on and retained there by friction. 70

The valves V' of the upper end sections or plungers will normally be open, because the weight of these valves, together with the weight of their stems, will cause them to drop downwardly. They will be supported by the contact of the corresponding valves V² upon the upper extremities of these end sections or plungers. This is not clearly shown in those drawings which are made upon a small scale, because there the valves V², belonging 80 to the upper end sections or plungers, are represented by a single line, and to clearly illustrate them by a single line it is necessary to show a space beneath them.

We will now give a detailed description of 85 the operation of the machine. Before the feeding of material the parts will be adjusted into the positions in which they are represented in Figs 1 and 2. The material to be treated will then be introduced into the receptacle H, and will of course fall into the upper part of the cavities of the movable plate A and rest upon the upper extremities of the lower series of end sections or plungers C'. Having supplied the material, the operator 95 shifts the valve of the engine R', in the present instance by pressing his foot against a treadle r¹⁰, which controls said valve. It is obvious that this treadle or lever could be operated periodically by a cam M, if desired. 100 The engine R' having been started, the lower end sections C², the movable plate A, and the receptacle H will be carried upward. As soon as the receptacle H reaches the bottom of the fixed plate B its movement will be arrested and the upward movement of the movable plate will bring it into contact with the bottom of the fixed plate B, whereupon its movement will cease. This condition of the machine is illustrated by Fig. 3. The arresting of the receptacle H and the movable plate A has no effect upon the end sections or plungers C², so the upward movement of these end sections or plungers continues and their upper extremities enter the cavities of 115 the fixed plate B and carry the material to be treated upward into these cavities. The upper end sections or plungers, it will be remembered, were at the beginning of the operation of the press in such position that 120 their lower extremities projected below the fixed plate. The upward movement of the platform r³ with the lower end sections or plungers, the movable plate A, and the receptacle H caused an upward movement of 125 the cord r⁸ and allowed the spring r⁶ to adjust the valve of the engine R². The operation of the engine R² effected the raising of the upper end sections or plungers C'. This movement will be understood by reference to Fig. 3, 130 where they are represented in their extreme upward position. In this position they remain until the lower end sections or plungers by their upward movement shall have pressed the

material to the desired degree between themselves, the upper end sections or plungers, and the sides of the cavities in the fixed plate. This compression is illustrated in Fig. 4. As 5 the lower end sections or plungers C^2 reach the end of their upward movement the stem of the valve g^5 contacts with the stop g^6 . The valve is thereby opened, and gas is admitted to the gas-chamber G^2 . This gas rises through 10 the passages of the end sections or plungers C^2 , opens the valves V' , and, having done this, enters the cavities c^2 of these end sections or plungers. The pressure of the gas will disengage the pressed articles from the 15 end sections or plungers C^2 as soon as the downward movement of the latter commences. The action of the gas is automatically regulated in proportion to the resistance offered to the opening of the valves V' , for, by being 20 cut off quickly from those end sections or plungers whose valves V' open easily, the gas will be concentrated on those other end sections or plungers whose valves V' require the exertion of greater force to open them. 25 The gas within the chamber G^2 acts upon the valves V^2 of the end sections or plungers C^2 , and by forcing them to their seats stops the further flow of gas into said end sections or plungers. The compression having been completed, the operator or the cam, if one be used, 30 releases the treadle or lever r^{10} and thus causes the lowering of the lower end sections or plungers, the movable plate, and the receptacle H , besides reversing the valve of the engine R^2 by pulling upon the cord r^8 . The reversal of the engine R^2 lowers the upper end sections or plungers C' until their lower 35 extremities protrude from the bottom of the fixed plate B . Thus the pressed articles or 40 cakes will be driven out of the fixed plate. The lowering of the gas-chamber G' with the upper end sections or plungers will cause the stem of the valve g^3 to contact with the stop g^4 . Thus the valve will be opened, gas will 45 be allowed to flow from the gas-chamber G' through the passages of the end sections or plungers C' to the end cavities of the latter, and in this way the cakes or pressed articles will be detached, provided they shall not have 50 before dropped off. By this time all the parts will have resumed the positions in which they are represented in Figs. 1 and 2. The detached articles may be caught in a tray T . (Represented in Fig. 2.)

55 In Fig. 12 the movable plate is made in two sections A' A^2 , which are detachably connected together, like the two parts of an ordinary die used for articles of celluloid, rubber, or plastic material of a similar nature. In 60 indeed, these two sections are precisely like the sections of a die used for materials of this class, excepting that their cavities are bottomless. The plastic material is intended to be introduced in the form of a sheet between 65 the two sections of the movable plate. In other respects the operation of the machine will be like that originally described.

The end section or plunger illustrated in Fig. 10 has no valve V' , but in lieu thereof a diaphragm of perforated or reticulated material V^3 . Instead of a valve V^2 attached to a stem, it has an ordinary flap-valve V' , which is attached at one point to the extremity of the end section or plunger.

What we claim as our invention, and desire to secure by Letters Patent, is—

1. In a press, the combination of two series of end mold-sections or plungers having a relative movement, a fixed mold-plate, and a movable plate, substantially as specified. 75 80

2. In a press, the combination of two series of end mold-sections or plungers, an engine for moving one of said series, a fixed mold-plate, a movable plate, and springs intermediate of the movable plate and the engine for transmitting motion from the engine to said movable plate, substantially as specified. 85

3. In a press, the combination of two series of end mold-sections or plungers, an engine for moving one of said series, a fixed mold-plate, a movable plate having cavities fitting one of said series of end mold sections or plungers, springs, and bolts for adjustably limiting the range of movement of the movable plate, substantially as specified. 90 95

4. In a press, the combination of two series of end mold-sections or plungers, an engine for moving one of said series, a fixed mold-plate, a movable plate, springs intermediate of the plate and the engine for transmitting motion from the engine to said movable plate, a receiver fitting round one end of the movable plate, and springs for supporting the receiver, substantially as specified. 100

5. In a press, the combination of two series of end mold-sections or plungers, an engine for moving one of said series, a fixed mold-plate, a movable plate, springs intermediate of the movable plate and the engine for transmitting motion from the engine to said movable plate, a receiver fitting round one end of the movable plate, springs for supporting the receiver, and adjustable bolts for limiting the movement of the receiver, substantially as specified. 105 110 115

6. In a press, the combination of two series of end mold-sections or plungers, two engines for imparting motion to the two series of end mold-sections or plungers, a connection between the valve of one engine and a part moved by the other engine, a valve controlling the engine last named, a fixed mold-plate, and a movable plate, substantially as specified.

7. In a press, the combination of a fixed mold-plate, two series of end mold-sections or plungers having passages through them, gas-chambers with which said end mold-sections or plungers communicate, and valves at the operative extremities of said end mold-sections or plungers, substantially as specified. 125 130

8. In a press, the combination of a fixed mold-plate, two series of end mold-sections or plungers having passages through them, gas-

chambers with which said end mold-sections or plungers communicate; valves at the operative extremities of said end mold-sections or plungers, and valves at the inner extremities of said end mold-sections or plungers, the two sets of valves belonging to each series of end mold-sections or plungers being connected together, substantially as specified.

9. In a press, the combination of a fixed mold-plate, two series of end mold-sections or plungers having passages through them, gas-chambers with which said end mold-sections or plungers communicate, valves controlling the ingress of gas to said chambers, and adjustable stops or tappets for effecting the opening of said valves, substantially as specified.

10. In a press, the combination of a fixed mold-plate, two series of end mold-sections or plungers; and a movable plate having cavities provided at the upper end with beveled or flaring mouths having rectangular extremities which are separated by narrow edges, substantially as specified. 20

In testimony that we claim the foregoing we hereunto set our names.

WOLCOTT A. HULL.
ARTHUR G. BOYER.
